UNITED STATES PATENT OFFICE

118,747

DESIGN FOR A PHONOGRAPH TONE ARM

Wesley E. Sharer, Chicago, Ill., assignor to S. N. Shure and Frances Shure, trustee, doing business as Shure Brothers, a partnership

Application January 30, 1939, Serial No. 82,682

Term of patent 7 years

To all whom it may concern:

Be it known that I, Wesley E. Sharer, a citizen of the United States, residing at Chicago, county of Cook and State of Illinois, have invented a new, original, and ornamental Design for a Phonograph Tone Arm, of which the following is a specification, reference being had to the accompanying drawing, forming a part thereof, in which:

Figure 1 is a top plan view of a phonograph tone arm, showing my new design; Fig. 2, a side view in elevation; and Fig. 3, a front view in elevation.

I claim:

The ornamental design for a phonograph tone arm, as shown.

WESLEY E. SHARER.
